CLAIM

The ornamental design for a bottle, as shown and described.

DESCRIPTION

FIG. 1 is a perspective view of a bottle showing my new design;

FIG. 2 is a front elevational view thereof;

FIG. 3 is a side elevational view thereof;

FIG. 4 is a top plan view, the opposite side being a mirror image thereof;

FIG. 5 is a rear elevational view thereof; and

FIG. 6 is a perspective view showing the bottle in an exploded condition.
